Attorney

UNITED STATES PATENT OFFICE

IVAN L. BLAKE, OF HANNIBAL, NEW YORK

ARMORED-CONDUIT-CUTTING TOOL

Application filed April 6, 1928. Serial No. 268,001.

The present invention relates to improvements in tools and has reference more particularly to an implement for cutting armored conduits that are constructed of metal ribbon wound into a spiral tube.

One of the important objects of the present invention is to provide a tool of this above mentioned character which will, at all times, be positive and efficient in its operation, the same being further simple in construction, inexpensive, strong and durable, and further well adapted to the purpose for which it is designed.

A further object resides in the provision of a cutting tool of the above mentioned character wherein a hook formed on one of the pivoted elements is formed with grooves, in its inner face, complementary to the grooves of the armored conduit, so that said conduit will properly fit against the inner face of the hook to facilitate the slitting of the conduit by swinging a pivoted cutter into engagement with the conduit.

Other objects of the invention will become apparent as the nature of the invention proceeds, and when taken in connection with the accompanying drawing.

In the accompanying drawing, forming a part of this application and in which like numerals designate like parts throughout the several views.

Figure 1 is a side elevation of the tool embodying my invention, showing the knife carrying lever in the act of swinging the knife into engagement with a portion of the flexible conduit engaged with the hooked end of the lever or handle.

Figure 2 is an edge elevation of the tool.

Figure 3 is a vertical sectional view through the hooked upper end of the lever showing the angularly disposed grooves formed in the inner face thereof and also showing the upper end portion of the knife carrying handle or lever, the knife blade being removed, 45 and

Figure 4 is a sectional view, taken approximately on the line 4—4 of Figure 2, looking in the direction of the arrows.

In the drawing, wherein for the purpose of illustration is shown the preferred embodiment of my invention, the numeral 1 designates a lever that is formed at its upper end with a forwardly and downwardly curved hook 2, and as is more clearly shown in Figures 2 to 4 inclusive, the inner face 55 of this hook is formed with the vertically disposed angular grooves 3, for cooperation with the armored conduit A that is constructed of metal ribbon which is wound around a spiral tube, in the manner well known in the art. The manner in which this armored conduit A engages with the grooved inner face of the hook 2 is clearly illustrated in Figure 1.

The lower end of the lever is curved 65 slightly as shown also in Figure 1.

The invention further comprehends the provision of the lever or handle 4, which is formed on one side at its upper end with a plate like extension 5, and as is more clearly 70 shown in Figures 1 and 3, the upper end portion of this lever is cut away as at 6, to form a shoulder against which the inner side face of the lever 1 engages, when the levers are brought together, a pivot bolt 7 extending 75 through the plate like extension 5, and the portion of the lever 1 below the hook 2, to afford a pivotal connection between the levers. A nut 8 is threaded on the threaded end of the bolt.

Forming a salient part of the present invention is the flat blade 9, that is riveted, or otherwise secured to the front side of the lever or handle 5, the securing means for the blade being shown at 10. The upper portion 85 of the blade projects above the upper end of the lever 4 and the bolt 7 extends through the upper portion of the blade and in this manner, the plate like extension 5 will be disposed against the rear side of the lever 1, 90

while the upper portion of the blade will be disposed against the front side of the said lever.

The upper edge portion of the blade 6 is sharpened to provide a cutting edge 11 and as is more clearly illustrated in Figure 1, this cutting edge is of serpentine shape and also one end of the cutting edge is higher than the other end for a purpose to be hereinafter more fully explained.

In use, the armored conduit A is engaged by the hooked end 2 of the lever 1, in the manner as shown in Figure 1, and the lever 4 is swung outwardly to an inoperative position so that said armored conduit can be properly engaged by the hook 2 and the grooves 3 formed in the inner face of the hook will properly engage with the convolutions of the conduit, so that said conduit will be effectively supported in the hooked upper end of the lever 1.

By swinging the free end of the lever or handle 4, which is also curved slightly inwardly, toward the lever 1, said lever 4 will swing on the pivot 7 to move the cutting edge 11 into engagement with the convolutions of the armored conduits at the bottom thereof.

The serpentine cutting edge 11 will slit the bottom portion of the armored conduit and by constructing the cutting edge of the blade in the manner shown, the same will effectively split the armored conduit.

The simplicity of my improved tool, enables the same to be readily and easily operated, and furthermore the tool can be manufactured at a very low cost and yet be strong and durable.

While I have shown the preferred embodiment of my invention, it is to be understood that minor changes in the size, shape, and arrangement of parts may be resorted to, without departing from the spirit of the invention and the scope of the appended claims.

Having thus described my invention, what I claim as new is:

1. In a tool for slitting armored conduits longitudinally, a lever, a conduit engaging hook formed on the upper end of the lever, an additional lever, a plate like extension on the rear side of said additional lever at the upper end thereof for disposition against the rear side of the first mentioned lever, a blade secured at its lower portion on the front side of the second lever, the upper end of said blade being projected against the front side of the first mentioned lever, a pivot pin extending through the blade and the plate like extension and through the first mentioned lever, the upper edge of the blade being sharpened for cutting engagement with the bottom portion of the armored conduit engaged by said hook.

2. In a tool for slitting armored conduits

longitudinally, a pair of pivotally connected levers, a conduit engaging hook formed on the upper end of one lever, the inner face of the hook being formed with means for engagement with the cable to prevent longitudinal movement of the latter, a blade secured on the other lever, the upper edge of said blade being formed with a serpentine cutting edge the rear salient of which is higher than the other for engagement with the bottom portion of the conduit, to slit the conduit longitudinally.

In testimony whereof I affix my signature.

IVAN L. BLAKE.
